UNITED STATES PATENT OFFICE.

THOMAS J. KEHOE, OF TOLEDO, OHIO, ASSIGNOR TO THE WILLYS-OVERLAND COMPANY, OF TOLEDO, OHIO, A CORPORATION OF OHIO.

RADIATOR FOR AUTOMOBILES.

1,416,837.

Specification of Letters Patent. Patented May 23, 1922.

Application filed June 15, 1917. Serial No. 174,928.

To all whom it may concern:

Be it known that I, THOMAS J. KEHOE, a citizen of the United States, residing at Toledo, in the county of Lucas and State of Ohio, have invented certain new and useful Improvements in Radiators for Automobiles, of which I declare the following to be a full, clear, and exact description.

This invention relates to improvements in radiator cores, such as are employed in the construction of radiators for automobiles. The principal object of this invention is to provide a radiator construction in which the cost of the metal employed can be reduced without lessening the effective radiation. Another object of my invention is to provide a radiator construction, which operates very efficiently to cool the water of the engine cooling system, and which can be produced and assembled rapidly and conveniently in large quantities and at a low cost.

Further objects and objects relating to economies of manufacture and details of construction will definitely appear from the detailed description to follow.

I accomplish the object of my invention in one instance by the devices and means described in the following specification but it is evident that the same may be varied widely without departing from the scope of the invention, as pointed out in the appended claims.

A structure constituting a preferred embodiment of my invention is illustrated in the accompanying drawings, forming a part of this specification, on which—

Fig. I is a view in front elevation of a radiator embodying my invention.

Fig. II is a detail, fragmentary, sectional view taken substantially on the line II—II of Fig. III, showing a portion of a radiator core constructed in accordance with my invention.

Fig. III is a detail, fragmentary, sectional view, taken substantially on the line III—III of Fig. II.

Fig. IV is a detail, fragmentary view in side elevation, of one of the water tubes.

Fig. V is a detail, perspective view showing one of the water tubes and a spacer between the water tube and the next adjacent water tube, and the connection of said tubes to the lower header.

Fig. VI is a detail, perspective view, show-

ing the connection of the water tube to the upper header.

In the drawings, similar reference numerals refer to similar parts throughout the several views, and the sectional views are taken looking in the direction of the little arrows at the ends of the section lines.

Considering the numbered parts of the drawings, the radiator 10 comprises an upper header 11 and a lower header 12, which are connected by the flat elongated water tubes or passages 15. The headers 11 and 12 are open at the bottom and top respectively, and provided with the in-turned flanges 13 and 14, which engage the tops and bottoms of said water tubes respectively, and as said tubes or passages form the sole connections between the upper and lower headers 11 and 12, the water of the engine cooling system which passes into the upper header 11, flows downwardly through the tubes 15 to the lower header as it is forced through the system.

In order to provide an effective radiator, it is desirable that as large a radiation surface as possible should be provided which is exposed to the current of air passing through the radiator to cool the water contained in said tubes or passages. Each of said water tubes 15 comprises the end portions 16, which are pressed together and in which are located the joints of said tubes, said tubes being otherwise seamless and without joints or cracks, and each of said tubes is provided at intervals with the laterally extending fins 17, which extend at right angles thereto and form hollow branches or arms, as clearly appears from Fig. II of the drawing. Intermediate the laterally extending arms or fins 17, grooves or depressions 18 are provided in the side walls of the tubes 15, in order to increase the radiation surface thereof. These water tubes are assembled together relative to the upper and lower headers, with the flat end portions 19 of said laterally extending arms or fins 17 resting on the flanges 13 and 14 of the upper and lower headers respectively, and flat spacing strips 20 are interposed between each pair of tubes, with the edges of the laterally extending arms or fins 17 engaging said sheets, as clearly appears from Figs. II and V of the drawings.

These strips of metal 20 not only serve

2
to space the water tubes relative to each other, but serve as radiation surfaces since they are in engagement with the edges of the laterally extending arms or fins on the 5 water tube and take heat therefrom, thus heating their surface which is exposed to the current of air passing through the radiator. The distance between the points at which said sheets 20 engage the laterally extending fins or arms 17 of the water tubes 10 is such that they act as efficient radiation surfaces, since these points are close enough together so that heat is readily transferred by convection to the strip of metal, and at 15 the same time, the strips will take up as much heat from the tubes as they can readily give up to the cooling air currents so that efficient radiation is secured.

The strips of metal 20 do not need to be 20 made of the same material as the tubes 15, but may be made of a cheaper or less expensive material since they do not come into contact with any water, and act merely as spacers and radiation surfaces. The ends 25 of the tubes are dipped in solder, after the whole radiator core is assembled together, which serves to close the seams and joints at the ends thereof, and to fasten the tubes with relation to the spacing strips 20, and this 30 also serves to seal the upper and lower headers and fasten the tubes relative thereto. Since there are no seams in said tubes, except at the ends thereof, it is only necessary to dip the ends thereof in solder and this 35 means a consequent large saving in the amount of solder necessary in the manufacture of radiator core.

I am aware that the particular embodiment of my invention, which I have here 40 shown and described, is susceptible of considerable variation, without departing from the spirit thereof, but I have found that this particular embodiment is desirable, and therefore I desire to claim my invention 45 both specifically and broadly, as indicated by the appended claims.

Having thus described my invention, what I claim as new, and desire to secure by Letters Patent, is—

50 1. In a device of the character described,

the combination of a header having an opening therein, a water tube unit connected therewith comprising a flat tubular portion, and a plurality of hollow arms communicating therewith and extending therefrom, 55 the lowermost of said arms resting upon said header and spanning said opening.

2. In a device of the character described, the combination of a header having an opening therein, a plurality of water tube units 60 in communication therewith, each of said units comprising a flat tube having hollow arms extending laterally from opposite sides thereof, a separating plate between adjacent units, the ends of the lowermost arms of said 65 units and said plates being secured directly to said header and serving to close the opening therein.

3. In a device of the character described, the combination of an upper and a lower 70 header, a water tube unit for connecting said headers comprising a flat tube having a plurality of laterally extending hollow arms 75 communicating therewith, the uppermost and lowermost arms having their walls pressed together at their end portions and secured to said headers.

4. In a device of the character described, the combination of an upper and a lower header having opposed openings, a plurality of water tube units each comprising a flat tube section having a series of hollow arms communicating therewith and extending laterally from each side thereof, metal plates contacting with the outer ends of said arms and separating adjacent units, the uppermost and lowermost arm of each series having its walls pressed together and secured to the adjacent header to close the opening therein. 90

5. In a device of the character described, the combination of a header having an opening therein, a water tube unit connected therewith comprising a flat tubular portion and a plurality of hollow arms communicating therewith and extending therefrom, certain of said arms engaging said header and spanning said opening. 95

In testimony whereof I affix my signature.
THOMAS J. KEHOE.
